CHARLES E. POST AND PAUL G. WAGNER, OF LOS ANGELES, CALIFORNIA.

LIQUID-SOAP DISPENSER.

1,319,898.

Specification of Letters Patent.

Patented Oct. 28, 1919.

Application filed October 25, 1916. Serial No. 127,684.

To all whom it may concern:

Be it known that we, CHARLES E. Post and PAUL G. WAGNER, citizens of the United States, residing at Los Angeles, in the 5 county of Los Angeles and State of California, have invented new and useful Improvements in Liquid-Soap Dispensers, of which the following is a specification.

Our invention relates to a soap dispenser 10 and particularly pertains to a container from which liquid soap may be dispensed.

The object of our invention is to provide a container for liquid soap or any other desired liquid which is equipped with simple 15 and efficient means entirely devoid of valves and delicate operative parts and which may be readily composed of non-corrodible materials whereby a predetermined volume of liquid will be discharged at each operation 20 and which will be entirely non-leaking between the intervals of operation, and which may readily be filled at any time without disturbing the operating mechanism thereof.

The invention is illustrated, by way of example, in the accompanying drawings in 25 which:

Figure 1 is a view in vertical cross section as seen through the reservoir and particularly discloses the detail construction of the 30 measuring valve and the actuating mechanism therefor.

Fig. 2 is a view in horizontal section and elevation as seen on the line 2-2 of Fig. 1 viewed in the direction of the arrows.

Fig. 3 is a view in horizontal cross section as seen on the line 3-3 of Fig. 1 and particularly illustrates the construction of the nozzle filling chamber and the nozzle opening communicating therewith.

Fig. 4 is a view in side elevation illustrating, upon a small scale, the assembled soap dispenser and support therefor.

Referring to the drawings more particularly, 10 indicates a soap reservoir which is 45 preferably formed of a vitreous or other non-corrodible material, such as glass. The reservoir is preferably pear-shaped, having its small end extending downwardly, as particularly shown in Fig. 1 of the drawings. Mounted over the lower end of the reservoir is a combined measuring and dispensing valve 11 which is formed with a valve cylinder 12 extending upwardly into the open end of the reservoir and having 55 a flange 18 adapted to bear against a packing washer 14 interposed between the end

of the reservoir and the upper face of said flange. Detachably secured beneath the cylinder 12 is a discharge nozzle 15 which is formed of non-corrodible material, which 60 provides an outlet for the liquid soap within the reservoir. This nozzle is formed with a central bore 16 which is counter-bored at its upper end to form a nozzle supply chamber 17. The lower end of the bore 16 is reduced 65 in diameter and communicates with a small outlet duct 18 leading into a spherical anti-drip orifice 19 from which the liquid soap is discharged or dispensed. The cylinder 12 and the nozzle 15 are held in position upon the lower end of the reservoir by a union nut 20 which engages suitable threads formed upon the reservoir and the union nut is screwed into a supporting ring 21.

Reciprocally mounted for movement 75 through the bore of cylinder 12 and into the nozzle bore 16 is a plunger or piston 22 which is fitted with a removable packing covering 22' adapted to maintain a close fit within the bores through which it moves. 80 This piston is preferably threaded upon the end of a plunger rod 23 which extends upwardly through the reservoir 10 and terminates within a top-cap 24. The upper end of the plunger rod is provided with a spring 85 washer 25 beneath which a coil spring 26 is positioned to bear upon a packing washer 27 mounted within a chambered recess 28 formed as a part of a lid 29 by which the receptacle is closed. A stop-collar 30 is 90 fixed to the plunger rod 23 beneath the face of the recess, thereby limiting the upward movement of the plunger as actuated by the spring 26. The lid 29 is adapted to rest upon a packing washer 31 and is held within 95 a sleeve 32 screwed upon the reservoir 10, by means of a lock-ring 33 which in turn is held in place by the top-cap 24 threaded to the outer periphery of the sleeve 32.

As a means for actuating the plunger rod 100 23 a push button 34 is provided and mounted upon a secondary plunger rod 35 which extends through bushing 36 into the top-cap 24 and into engagement with the upper end of the plunger rod 23, thereby making it 105 possible for the plunger rod and press button to move simultaneously when it is desired to obtain soap from the reservoir.

The assembled dispenser may be mounted 110 in a convenient position for operation in any desired manner. In Fig. 4 of the drawings it is shown as mounted upon a horizon-

tally secured bracket 37, integral with the ring 21, which is held by screws to the face of the wall or other finish boards.

In operation, the various vital parts of the 5 dispenser will be normally positioned as illustrated in Fig. 1 of the drawings, at which time a measured quantity of liquid soap will be suspended within the nozzle bore 16. When it is desired to obtain soap from the 10 dispenser, the push button 34 is depressed and this in turn will actuate the plunger rod 23 to move the piston 22 in a downward direction. During the course of the downward travel of the plunger, it will pass from 15 the bore in cylinder 12 and down to the lower end of the bore 16 of the nozzle. At the same time the quantity of soap within the bore 16 will be forcefully discharged through the duct 18 and may be caught in 20 any desired manner. As the piston 22 is depressed, the soap in the reservoir 10 will obviously follow the same and as said piston passes through the chamber 17 it primarily displaces a volume of air less than the total 25 piston volume. This is due to the fact that the length of the piston is greater than the depth of the chamber 17. This partial displacement of air results in air pressure which is first exerted upon the soap in the chamber 16, the upper portion of which becomes 30 partially filled with air before the lower end of the piston closes the upper end of said chamber, the air being thus trapped between the piston and the soap in the chamber 16. This insures a complete emptying 35 of the chamber 16 so that upon the return stroke of the piston there is no resistance to the intake of air and consequently no foaming of the soap due to the passage of 40 the admitted air in a fine stream through a small body of soap contained in the chamber 16.

During the downward movement of the piston, soap from the reservoir 10 will follow until the upper end of the piston has passed the lower or discharge end of the 45 passage or cylinder 12.

Further downward travel of the piston causes a partial vacuum to be formed in the 50 chamber 17 thus further forcing continuation of flow of the soap from the reservoir 10 into said chamber 17.

The return stroke of the piston causes the 55 chamber 16 to become filled with air and as said piston again passes through the chamber 17, it displaces some of the fluid therein and this forces a predetermined volume thereof to pass into the reservoir 10. Normally this fluid will be air but in the event that the 60 piston is forcibly maintained at the lower limit of its movement until the chamber 17 is entirely filled with soap, then part of that soap will be returned to the reservoir 10. As the piston approaches and until and after it 65 reaches the upper limit of its movement, air

from the chamber 16 will pass into and substantially fill the chamber 17 while the soap contained in the latter flows into and fills the chamber 16.

It will be seen from the foregoing that the 70 action of the device is positive and depends in no way upon gravity.

When it is necessary to refill the reservoir with a soap solution, the top cap 24 carrying the push button is removed. By withdraw- 75 ing the stopper 39, the reservoir may be re-filled. Where it is desired to replace the packing on the plunger or to clean the interior of the reservoir, although such cleaning will not be necessary, except at great intervals for the reason that the parts with which the soap come in contact are non-corrodible, and the reservoir is entirely closed, then the lid 29 is removed, after taking off the closure ring 33. 80

The first actuation of the plunger will discharge a full quantity of liquid soap contained in the bore 16, but if immediately thereafter the push button 34 is rapidly reciprocdated, little or no soap will be discharged through the discharge orifice. This is due to the fact that insufficient time is allowed for the air to bubble up through the liquid soap or for the soap to flow into the nozzle supply chamber. We consider this 95 action of our dispensing device of great advantage, as it prevents waste of soap so common with the ordinary soap dispenser now in use. 90

It will be understood that various changes 100 in the construction, combination and arrangement of parts may be made by those skilled in the art without departing from the spirit of our invention as defined in the claims. 105

Special attention is called to the fact that the soap dispenser may be refilled from time to time without in any way disturbing or removing the piston mechanism and that when the soap dispenser is ready for operation it has no vent except the discharging 110 orifice.

Attention is also called to the means forming the piston bore and having an enlarged measuring chamber intermediate of the ends 115 of the piston bore, the piston being normally in the upper end of the piston bore, thereby forming a partial vacuum below the piston to prevent leakage through the discharge orifice. 120

We claim:

1. A liquid soap dispenser comprising a reservoir having a cylindrical discharge orifice at its lower end, an air chamber below the same, and a cylindrical container 125 for a predetermined volume of soap below said air chamber axially aligned with said orifice, the last-named container having an unobstructed minute discharge opening, a piston reciproable and normally disposed 130

in the cylindrical discharge orifice and snugly fitting the same and adapted to be depressed to pass out of the same and into the container to forcibly eject the contents 5 of the latter and at the same time permit passage of soap from said reservoir into said air chamber and upon its return stroke permit passage of air from said air chamber into said reservoir, the said return stroke 10 causing air to fill said cylindrical container and pass into said air chamber whereupon soap will flow from the latter into said container to substantially refill the same.

2. A liquid soap dispenser comprising a 15 reservoir having a cylindrical discharge orifice at its lower end, an air chamber below the same, and a cylindrical container for a predetermined volume of soap below said air chamber axially alined with said 20 orifice, the last-named container having an unobstructed minute discharge opening, a piston reciprocable and normally disposed in the cylindrical discharge orifice and snugly fitting the same and adapted to be 25 depressed to pass out of the same and into the container to forcibly eject the contents of the latter and at the same time permit passage of soap from said reservoir into said air chamber and upon its return stroke 30 permit passage of air from said air chamber into said reservoir, the said return stroke causing air to fill said cylindrical container and pass into said air chamber whereupon soap will flow from the latter into said 35 container to substantially refill the same, said piston snugly fitting and substantially filling said container when disposed therein.

3. A liquid soap dispenser comprising a 40 reservoir having a cylindrical discharge orifice at its lower end, an air chamber below the same, and a cylindrical container for a predetermined volume of soap below said air chamber axially alined with said 45 orifice, the last-named container having an unobstructed minute discharge opening, a piston reciprocable and normally disposed in the cylindrical discharge orifice and snugly fitting the same and adapted to be 50 depressed to pass out of the same and into the container to forcibly eject the contents of the latter and at the same time permit passage of soap from said reservoir into said chamber and upon its return stroke permit 55 passage of air from said air chamber into said reservoir, the said return stroke causing air to fill said cylindrical container and pass into said air chamber whereupon soap will flow from the latter into said 60 container to substantially refill the same, said air chamber being of larger diameter than said container and of less depth than the length of said piston.

4. A liquid soap dispenser comprising a 65 reservoir having a cylindrical discharge

orifice at its lower end, an air chamber below the same, and a cylindrical container for a predetermined volume of soap below said air chamber axially alined with said orifice, the last-named container having an 70 unobstructed minute discharge opening, a piston reciprocable and normally disposed in the cylindrical discharge orifice and snugly fitting the same and adapted to be depressed to pass out of the same and into 75 the container to forcibly eject the contents of the latter and at the same time permit passage of soap from said reservoir into said air chamber and upon its return stroke permit passage of air from said air chamber 80 into said reservoir, the said return stroke causing air to fill said cylindrical container and pass into said air chamber whereupon soap will flow from the latter into said container to substantially refill the same, said piston snugly fitting and substantially filling said container when disposed therein, said air chamber being of larger diameter than said container and of less depth than the length of said piston.

5. A liquid soap dispenser comprising a reservoir having a cylindrical discharge orifice at its lower end, an air chamber below the same, and a cylindrical container for a predetermined volume of soap below said 95 air chamber axially lined with said orifice, the last-named container having an unobstructed minute discharge opening, a piston reciprocable and normally disposed in the cylindrical discharge orifice and snugly fitting 100 the same and adapted to be depressed to pass out of the same and into the container to forcibly eject the contents of the latter and at the same time permit passage of soap from said reservoir into said chamber and upon 105 its return stroke permit passage of air from said air chamber into said reservoir, the said return stroke causing air to fill said cylindrical container and pass into said air chamber whereupon soap will flow from the latter into said container to substantially refill the same, said air chamber being of larger 110 diameter than said container and of less depth than the length of said piston, and of approximately equal volume with said container.

6. A liquid soap dispenser comprising a reservoir terminating at its lower end in a discontinuous cylindrical discharge orifice comprising two parts separated from each 120 other by an annular air chamber, a piston reciprocable in said orifice and of greater length than the depth of said air chamber, means for manually depressing said piston, a spring for supporting the same and maintaining it normally disposed in said orifice above said air chamber, said piston adapted to substantially fill the lower end portion of said orifice when depressed and to be then disposed so that its upper end is substantially 125 130

flush with the bottom of said air chamber, there being an unobstructed minute discharge opening in the lower end of the last-named portion of said orifice through which the contents of the latter are discharged as said piston enters said part.

7. A liquid soap dispenser comprising a reservoir terminating at its lower end in a discontinuous cylindrical discharge orifice comprising two parts separated from each other by an annular air chamber, a piston reciprocable in said orifice and of greater length than the depth of said air chamber, a piston rod for said piston extending through said reservoir and projecting through the top wall thereof, a spring supporting said

rod for maintaining said piston normally disposed in said orifice above said air chamber, said piston adapted to substantially fill the lower end portion of said orifice when depressed and to be then disposed so that its upper end is substantially flush with the bottom of said air chamber, there being an unobstructed minute discharge opening in the lower end of the last-named portion of said orifice through which the contents of the latter are discharged as said piston enters said part.

In testimony whereof we have signed our names to this specification.

CHARLES E. POST.
PAUL G. WAGNER.
